UNITED STATES PATENT OFFICE.

FREDERICK DIEHL, OF ELIZABETH, NEW JERSEY, ASSIGNEE TO THE SINGER MANUFACTURING COMPANY, OF ELIZABETH, NEW JERSEY, A CORPORATION OF NEW JERSEY.

MOTOR-DRIVEN SEWING MACHINE.

Application filed August 24, 1921. Serial No. 495,015.

To all whom it may concern:

Be it known that I, FREDERICK DIEHL, a citizen of the United States, residing at Elizabeth, in the county of Union and State of New Jersey, have invented certain new and useful Improvements in Motor-Driven Sewing Machines, of which the following is a specification, reference being had therein to the accompanying drawings.

10 This invention relates to motor driven sewing machine outfits and has for an object to provide such an outfit with a concealed motor drive which will require a minimum of attention to keep it in proper 15 operative condition.

Another object of the invention is to provide a sewing machine outfit with a concealed motor drive occupying a minimum of space below the sewing machine base-20 plate, whereby the sewing head may be installed in either a hand carrying case or drop-head cabinet of minimum size and capacity.

25 Further objects of the invention will appear as the description proceeds.

In the present embodiment of this invention, the sewing machine base-plate which fits the top opening in the usual drop-head cabinet or in the hollow base member 30 of a hand-carrying case, has mounted thereon a sewing head of a well known type having a raised cloth-plate below the level of which is mounted the main sewing machine shaft. The driving motor is preferably of the well known type having a flattened frame and is mounted on a bracket secured to the under side of the base-plate. The motor is connected to the main-shaft of the sewing machine by means of a belt 35 which runs over grooved pulleys on the motor and sewing machine shafts and also runs over a grooved idler pulley at the end of a spring pressed idler arm secured to the motor bracket. A motor controller of the 40 knee-shift type, disclosed in the patent to Martin Heinleb, No. 1,444,917 of Feb. 13, 1923 is also preferably incorporated in the outfit when the sewing head is installed in the hollow base member of the carrying case. 45 This controller is situated alongside the space occupied by the motor, thus effecting a very compact and efficient arrangement. All wiring is concealed and protected within the hollow base member and there are no

exposed parts which are likely to get out of order.

On account of the compact arrangement of the concealed motor drive, the sewing head may also be installed in a drop-head cabinet, the cavity of which is of minimum width from front to back; a minimum clearance in rear of the usual hinge pins being necessary.

In the accompanying drawings, Fig. 1 is a side elevation, partly in section, of a sewing machine outfit embodying the invention. Fig. 2 is a top plan view of the hollow base member of the carrying case, with the motor and controller in their respective positions within the same. Fig. 3 is a section on the line 3—3, Fig. 2, with the sewing machine head superposed thereon. Fig. 4 is a section on the line 4—4, Fig. 2. Fig. 5 is a section on the line 5—5, Fig. 3, and Fig. 6 is a sectional view of the motor showing the flattened frame construction.

In the embodiment of the invention chosen for the purposes of the present disclosure, 1 represents the hollow rectangular base member of the usual sewing machine carrying case, the open top side of which base member is closed by a base-plate 2 having the usual hinge-pin connections 3 therewith and resting upon the ledges 4, Fig. 2.

The base-plate 2 may support above its plane a complete sewing head comprising a pedestal 5, raised cloth-plate 6, bracket-arm 7, needle 8, presser-foot 9 and feed-dog 10. The main-shaft 11 of the sewing machine 90 may be mounted below the level of the cloth-plate and carry a rotary chain-stitch looper 12.

The motor 13 preferably has a flattened field frame, the oppositely disposed faces 95 13' of which are in parallelism with the base-plate 2; a screw connection 14 being made with the inclined bracket 15 which is secured by screws 16 to the thickened seat 17 at the under side of the base-plate. It is 100 not necessary that the motor frame have oppositely disposed flat faces so long as its field frame is flattened in the sense that it is of greater width than height and is in a general sense mounted in substantial parallelism with the base-plate; i. e. with its maximum widthwise dimension substantially horizontal.

The motor shaft 18 is thus enabled to be placed a minimum distance below the base-plate 2 and is provided with a belt pulley 19. Secured to the bracket 15 by the pivot screw 20 is the spring-pressed arm 21, carrying the idler pulley 22, the spring 23 tending to swing the arm 21 downwardly, Fig. 3, and maintain a certain tension on the belt 24 which runs over the pulleys 19, 22 and the large pulley 25 on the sewing machine shaft 11.

A motor controller, preferably of the knee-shift type, having the constructive features disclosed in said Hemleb application, may be mounted within the hollow base 1 so as to occupy space alongside the space taken up by the motor 18. Such a controller comprises an iron box 26 enclosing the resistance unit 27 including the usual resistor-connected contact points 28 and the swinging contact arm 29 having a groove 30 which receives the pin 31 depending from the arm 32 pivoted at 33 to the box 26. The arm 32 is formed with an aperture 34 which receives the upper end of the arm 35 rigid with the rock-shaft 36 journaled in the box 26 and having an out-board projection 37 to which is detachably secured the upper end 38 of a knee-shift lever 39. The spring 40 restores the controller to "off" position, Fig. 2, when pressure of the knee against the lever 39 is relieved.

A partition 41 divides the base 1 into two compartments 42 and 43, within the latter of which the motor and controller are housed. The compartment 42 may be used as a receptacle for sewing machine attachments,

spools of thread, or other accessories, which are thus protected against being soiled or damaged by contact with the motor or other machine parts.

The usual plug terminals 44 are provided for connecting the motor and controller circuits to a suitable current supply.

It will be observed that the motor and controller, as incorporated in the portable case, are entirely concealed within the hollow base 1, and that the outfit may be set up for use on an ordinary table without in any way mutilating the latter.

Having thus set forth the nature of the invention, what I claim herein is:—

The combination with the usual hollow rectangular base of a sewing machine hand-carrying case having a flat bottom adapting it to rest for use upon an ordinary table, of a flat plate removably closing the top opening in said base, a sewing head having a frame casting formed with a pedestal 60 mounted on the upper side of said flat plate, said sewing head also having a cloth-plate raised above the level of the bottom of said pedestal and a main-shaft disposed below the level of the cloth-plate, a motor mounted on the under side of said flat plate within the cavity of said hollow base and having a frame flattened at opposite sides and disposed with its flat sides substantially parallel to and closely adjacent said plate and the bottom of the base of said carrying case, respectively, and a driving connection between said motor and said main-shaft.

In testimony whereof, I have signed my name to this specification.

FREDERICK DIEHL.
